INVENTOR,
Oliver B. Deatley,

By Minturn & Minturn,
Attorneys.

UNITED STATES PATENT OFFICE.

OLIVER B. DEATLEY, OF INDIANAPOLIS, INDIANA.

OIL-WASTE RETAINER.

Application filed October 17, 1925. Serial No. 63,135.

To all whom it may concern:

Be it known that I, OLIVER B. DEATLEY, a citizen of the United States, residing at Indianapolis, in the county of Marion and State of Indiana, have invented certain new and useful Improvements in Oil-Waste Retainers, of which the following is a specification.

My invention relates to means for retaining oil waste within journal boxes and the like, and has for its primary object the prevention of the waste packed below a journal from working around into the journal bearing surfaces, as well as up and away from the lubricant.

Other objects reside in the low cost of production, the adaptability to journal boxes already in use, and in the detachability of the retainer from the journal box.

A serious trouble encountered in railroad operation is the failure of lubrication in the journal boxes of the cars. These journal boxes are designed to be packed periodically with waste and oil such that the waste is packed below the journal to contact the journal from the under side.

Frequently, the waste so packed will be carried around the journal as it revolves such that the waste particles are carried around under the bearing brass with a resultant heating of the bearing, or the waste is so carried around or so works out, that the waste is lifted from the lower floor of the journal box such that the oil drains down out of the waste to the space left below and out of contact with the journal, and the bearing again heats due to lack of lubrication.

I overcome these difficulties and achieve the above indicated and such other minor objects as will be apparent in the following description, by the means as illustrated in the accompanying drawing, in which—

Fig. 1 is a perspective view of my oil-waste retainer; and Fig. 2, a diagrammatic longitudinal, vertical section through a journal box showing the relative position of the retainer within the journal box.

Like characters of reference indicate like parts in the two views.

Referring to Fig. 1, I form my oil-waste retainer preferably from sheet metal with a front attaching plate 5, a horizontal apron 6

having the vertical legs 7 and 8 projecting from its sides, and the horizontal fingers 9 and 10 extending from the legs 7 and 8.

The back edges of the apron 6, and the legs 7 and 8, and the lower edges of the fingers 9 and 10 are provided with laterally projecting teeth 11, here shown as being formed by cutting the metal edges at intervals and alternatingly bending the sections from one side to the other.

In applying my oil-waste retainer to the journal box, the box 12, Fig. 2, is first packed with the oiled waste 13 in the usual and customary manner by compressing the waste 13 below the journal 14. My retainer is then slipped within the box 12, on top of the waste, with the journal 14 lying between the fingers 9 and 10, and the attaching plate 5 is rested on the inclined front face 15 of the journal box 12 and secured thereto by bolts 16, such that the apron 6 comes on a line approximately at the under side of the journal 14. The space between the journal box side wall and the journal is comparatively small but permits the easy passage of the retainer fingers 9 and 10 therebetween without contacting either the wall or the journal.

The waste can not work out forwardly from under the journal 14 by reason of the apron 6 acting as a closure, and the teeth 11 on the apron and the vertical legs 7 and 8 effectively prevent the waste from working around the edge of the apron and forwardly from the space between the journal and the vertical walls of the journal box 12. Similarly, the teeth 11 on the edges of the horizontal fingers 9 and 10 prevent the waste from working upwardly around the journal 14 on either side.

Having described my invention in the form as now best known to me, it is obvious that the structure may be varied without departing from the spirit of the invention, and I therefore do not want to be limited to the precise structure as shown, nor any more than may be necessitated by the following claims.

I claim:

1. In a journal box having a journal extending therein, an oil-waste retainer having an attaching plate, an upright member extending from the plate on each side of the journal, a finger extending rearwardly from

the upper end of each upright member on each side of the journal, and waste retaining prongs on the fingers.

2. In a journal box having a journal extending therein, an oil-waste retainer having an attaching plate, an apron extending toward the journal near its under side and above the floor of the journal, a member ex-

tending upwardly from each side of the apron, a finger extending rearwardly from the top portion of each of the upright members, said fingers lying on each side of the journal, and retaining prongs on the fingers. 10

In testimony whereof I affix my signature.

OLIVER B. DEATLEY.
